UNITED STATES PATENT OFFICE.

WILLIAM E. BERTRAM, OF BROOKLYN, NEW YORK, ASSIGNOR TO INTERTYPE CORPORATION OF NEW YORK, N. Y., A CORPORATION OF NEW YORK.

STOP MECHANISM FOR LINOTYPE-MACHINES.

1,194,937.

Specification of Letters Patent. Patented Aug. 15, 1916.

Application filed September 13, 1912. Serial No. 720,293.

To all whom it may concern:

Be it known that I, WILLIAM E. BERTRAM, a citizen of the United States, residing at Brooklyn, in the county of Kings and State of New York, have invented new and useful Improvements in Stop Mechanism for Linotype-Machines, of which the following is a specification.

The present invention relates to improvements in linotype machines, and the primary object is to provide improved stop mechanism therefor whereby the stopping of the machine after completing each cycle of operations is effected without rebound or jar and the driving clutch is positively locked in inoperative condition with the parts of the machine occupying a predetermined relation, and the starting of the machine is effected easily and by slight pressure. In linotype machines as commonly used the movements of the machine are obtained from a main cam shaft which carries relatively large and heavy cams, and this cam shaft usually makes one complete revolution and then stops during each cycle of operations, although the cam shaft is occasionally stopped temporarily before completing a revolution. In practice, it has been found that considerable rebound and shock occurs in the operation of linotype machines as commonly constructed due to the inertia of the relatively heavy cams on the cam shaft, this objection being obviated by the present invention, and also the present invention enables the cam shaft to be stopped accurately at a predetermined point and the machine may be re-started easily and by a slight pressure by the operator, or by the usual automatic means.

To these and other ends, the invention consists in certain improvements, and combinations and arrangements of parts, all as will be hereinafter more fully described, the novel features being pointed out particularly in the claims at the end of the specification.

In the accompanying drawing: Figure 1 represents a side elevation, partly in section, of a portion of a linotype machine equipped with stop mechanism constructed in accordance with the present invention; Fig. 2 is a detail plan view of the driving clutch and the controlling means therefor; Figs. 3 and 4 show the non-rebound stop for arresting rotation of the main cam shaft after the latter has completed each revolu-

tion, the parts being shown in locked and unlocked condition, respectively; Fig. 5 is a detail view of the non-rebound stop showing the unlocking device; Fig. 6 is a perspective view of the non-rebound stop, the co-operative pawl on the main cam shaft, and a portion of the clutch-controlling connections.

Similar parts are designated by the same reference characters in the several views.

The present invention is particularly applicable to the well known linotype machine, and although the invention is not necessarily restricted to a machine of that specific type, the present embodiment of the invention is shown as applied to a linotype machine. In the present instance, 1 designates the main cam shaft which carries the relatively large and heavy cams which produce the different movements of the machine, this cam shaft being driven by a gear 2 which meshes with a pinion 3 on the power shaft 4, the latter being provided with a driving wheel 5 having a clutch drum 6 with which a pair of clutch shoes 7 co-operates, these clutch shoes in the present instance being operatively connected to the toggle links 8 and these toggle links being connected to a cross-head 9, the latter co-operating with an operating rod 10. The rod 10 is movable axially within the driving shaft 4 and is provided with a spring 11 which tends normally to spread the toggle links 8 and thereby force the clutch shoes 7 into driving engagement with the clutch drum on the wheel 5. The rod 10 has a collar 12 attached thereto, this collar being slidable on the exterior of the power shaft 4 and is adapted to be engaged by an arm 13 of a bell-crank 14, the latter being pivoted at 15 to a portion 16 of the frame of the machine, and the other arm 17 of the bell-crank is adapted to be engaged by one end of a bar 18, the latter being guided at its opposite end by the pin 19 and is operatively connected by a link 20 to a hand lever 21; this hand lever turning about the pin 19 as a center. The operation of the machine may be interrupted manually by manipulation of the hand lever 21 whereby the bar 18 is pushed against the arm 17 of the bell-crank lever and the arm 13 of the latter forces the collar 12 to the right in Fig. 2, thereby overcoming the action of the spring 11 and causing the toggle links 8 to 110

disengage the clutch shoes 7 from the clutch drum 6 of the driving wheel.

The automatic means for arresting rotation of the main cam shaft after the latter has completed each revolution is constructed as follows:—The main cam shaft 1 carries a cam 22 and this cam carries a pawl 23 which is movable laterally in a notch 24 of the cam, the pawl coöperating, according to the present invention, with a non-rebound stop 25 which is pivoted at 26 on the vertical stationary shaft 27 so as to swing in substantially the plane of revolution of the pawl 23 and normally occupies a position in the path of the pawl. An abutment 28 is rigidly secured to the vertical stationary shaft 27 and is provided with a shoulder 29 which is adapted to coöperate with the under side of the stop 25 when the latter is swung downwardly into the position indicated in Fig. 3. A stop lever 30 is pivoted at 31 to the shaft 27, the lower end of this stop lever being arranged to coöperate with the arm 17 of the bell-crank lever 14 and the upper end of the stop lever 30 is attached to a toggle composed of the links 32 and 33, one of the links, the link 32 in the present instance, having a projection 34 which is adapted to be engaged and depressed by the stop 25 whereby the toggle is moved from the unlocked position, as shown in Fig. 4, into the locked position as shown in Fig. 3, the pivotal centers of the toggle while in the latter position being in alinement and, hence, the toggle is capable of positively locking the clutch spring 11 from operation to engage the clutch. The toggle is unlocked, however, by a lever 35 which is pivoted at 36 to the rigid arm 28, one end of this lever coöperating with the center pivot 37 of the toggle while the opposite end of the lever is adapted to occupy a position at one side of the pawl or dog 23. A shell 38 is rotatably mounted on the shaft 27, the lower end of this shell being provided with an arm 39 which is arranged to be engaged by the projection 40 on the bar 18, and the upper end of the shell is provided with an arm 41 which is arranged normally at one side of the path of the pawl or dog 23, but when the bar 18 is operated by the hand lever 21 to engage the clutch, the projection 40 on the bar will operate upon the arm 39 of the shell, thereby rotating the latter and causing the arm 41 to move the pawl 23 laterally into its notch 24, thereby disengaging the pawl from the stop 25 and at the same time rocking the lever 35, this lever operating to unlock the toggle, the toggle and stop being restored to the condition shown in Fig. 4 and in readiness to arrest rotation of the cam shaft upon completion of its succeeding revolution. The yielding resistance offered to the pawl 23 by the toggle and its associated parts operates to absorb the shock

incident to the arresting of rotation of the relatively heavy cam shaft, thereby causing the cam shaft to be stopped without rebound or jar, and when the toggle has been operated, it not only disengages the clutch, but positively locks the clutch in disengaged condition, although re-starting of the machine can be effected easily and with relatively light pressure of the operating handle, as it is only necessary to disengage the pawl on the cam shaft laterally from the stop and to unlock the toggle, the clutch spring then acting to set the clutch in driving condition. With a machine equipped with stop mechanism embodying the present invention, the operator may turn the cam shaft backward by hand after this shaft has been stopped automatically, without the necessity of manipulating the hand-starting lever as heretofore.

What is claimed is:—

1. In a linotype machine, the combination of a main cam shaft, a driving clutch therefor, a member carried by the cam shaft for disengaging the clutch and arresting rotation of the cam shaft, and a locking device interposed between said member and the clutch for positively locking the clutch in disengaged condition and permitting retrograde rotation of the cam shaft. 95

2. In a linotype machine, the combination of a main cam shaft, a driving clutch therefor, means carried by the cam shaft for disengaging the clutch and arresting rotation of the cam shaft, and automatic means independent of the cam shaft for positively holding the clutch in disengaged condition. 100

3. In a linotype machine, the combination of a main cam shaft, a driving clutch therefor, means carried by the cam shaft for disengaging the clutch, and a lock operated automatically by said means to positively disengage the clutch and to hold the same in disengaged condition independently of the cam shaft. 110

4. In a linotype machine, the combination of a main cam shaft, a driving clutch therefor having a spring for engaging it, means carried by the cam shaft for disengaging the clutch, and a device movable in opposition to the action of the clutch spring to yieldably arrest said means on the cam shaft and operative to disengage the clutch and lock the same in disengaged condition. 115

5. In a linotype machine, the combination of a main cam shaft, a driving clutch therefor, a member carried by the cam shaft to control the clutch, and a toggle movable by said member into a position to disengage the clutch and to lock the clutch in disengaged position. 120

6. In a linotype machine, the combination of a main cam shaft, a driving clutch therefor, a member carried by the cam shaft to control the clutch, a toggle actuated by said 130

member to disengage said clutch and to lock the clutch in disengaged condition, and a lever operated through said member to release the lock.

5 7. In a linotype machine the combination of a main cam shaft, a driving clutch therefor, a member carried by the cam shaft to control the clutch, a stopping member, and a positive stop coöperative with said stopping member to arrest the cam shaft at a

certain point in its revolution and operative to positively lock the clutch in a disengaged condition.

In testimony whereof I have hereunto set my hand in presence of two subscribing witnesses.

WILLIAM E. BERTRAM.
